Primary Examiner—James M. Gandy*Attorney, Agent, or Firm*—Evenson, Wands, Edwards, Lenahan & McKeown**[57] CLAIM**

The ornamental design for a front face of a vehicle wheel, as shown and described.

DESCRIPTION

FIG. 1 is a front elevation view of a front face of a vehicle wheel embodying my novel design; and,

FIG. 2 is a perspective view thereof.

The broken line showing of a tire in the drawing is for illustrative purposes only and forms no part of the claimed design.

FIG. 1

FIG. 2
